UNITED STATES PATENT OFFICE.

MAX VON RECKLINGHAUSEN, OF NEW YORK, N. Y., ASSIGNOR, BY MESNE ASSIGNMENTS, TO COOPER HEWITT ELECTRIC COMPANY, A CORPORATION OF NEW YORK.

PROTECTING DEVICE FOR GAS OR VAPOR ELECTRIC LAMPS.

SPECIFICATION forming part of Letters Patent No. 721,741, dated March 3, 1903.

Application filed March 28, 1902. Serial No. 100,368. (No model.)

To all whom it may concern:

Be it known that I, MAX VON RECKLINGHAUSEN, a subject of His Majesty the Emperor of Germany, and a resident of New York, in the county of New York and State of New York, have invented certain new and useful Improvements in Protecting Devices for Gas or Vapor Electric Lamps, of which the following is a specification.

10 In gas or vapor electric lamps—say of the well-known “Cooper Hewitt” type—one or both of the electrodes is generally of mercury, and owing to the great weight of this substance there is more or less danger of the 15 lamps being broken or injured in being carried from place to place or in being handled without special care at any place.

The object of the present invention is to provide against these dangers by so constructing 20 these lamps as to provide special pockets for the mercury during travel, whereby the strain of the considerable weight of the mercury is to some extent relieved and in any case is brought to bear upon other parts than 25 those most likely to yield to such strain. I may develop the usual condensing-chamber of a Cooper Hewitt lamp into such a pocket, or I may blow out a special pocket on any part of the lamp-tube.

30 The accompanying drawings illustrate various arrangements for accomplishing the result aimed at, as will presently appear.

In the drawings, Figures 1 and 5 are sectional views of the same lamp in reversed positions, showing the condensing-chamber developed into a pocket; and Figs. 2, 3, and 4 illustrate different arrangements of pockets or their equivalent. In every instance except in Fig. 1 the lamps are shown in the position which they should occupy when ready 40 for shipment.

In Fig. 1 the condensing-chamber 4 of a Cooper Hewitt lamp is developed into a pocket, at the bottom of which, when the lamp 45 is prepared for shipment, the mercury 5 is located. This particular lamp is designed to

have two mercury electrodes—one connected with the leading-in wire 7 and the other connected with the leading-in wire 8. When operated, the lamp will be in the position shown 50 in Fig. 1, the mercury finding its way first into the pocket which the leading-in wire 7 enters, and the overflow passing then to the pocket at the opposite end of the lamp and there forming the second or negative electrode. Fig. 2 again shows the chamber 4 developed into a pocket for holding the mercury 5, the shipping position of the lamp being such that the main tube of the lamp lies horizontal. 55

In Figs. 3 and 4 are shown special pockets 10 10, blown on different parts of the lamp-body and adapted to contain the mercury, which can at will be distributed from the pockets to the proper parts of the lamp to 60 form the electrodes.

The condensing-chambers of Cooper Hewitt lamps have generally been constructed with the leading-in wire entering at the extremity thereof. This has caused a contraction 70 of the chamber at that point, and it is these contracted portions that are particularly weak and unable to resist the weight or shock of the mercury. The chamber illustrated in Fig. 5 is rounded out at the end to 75 obviate this weakness. In this sense I regard the chamber therein illustrated as a specially-constructed pocket in the same way as the pockets illustrated in Figs. 2, 3, and 4.

What I claim as my invention is— 80
In a gas or vapor electric lamp, the combination with the lamp-tube containing mercury for one or both of the electrodes, of a specially-constructed pocket for containing the mercury during transportation. 85

Signed at New York, in the county of New York and State of New York, this 20th day of March, A. D. 1902.

MAX VON RECKLINGHAUSEN.
